US00D332314S

United States Patent [19]

Torai et al.

[11] Patent Number: Des. 332,314

[45] Date of Patent: ** Jan. 5, 1993

[54] CLINICAL CHEMISTRY ANALYZER

[75] Inventors: Kazuki Torai, Kokubunji; Kazunori Hashimoto, Tachikawa; Isamu Takekoshi; Mitsuru Ohnuma, both of Tokyo; Hiroshi Satake, Katsuta, all of Japan

[73] Assignee: Hitachi, Ltd., Tokyo, Japan

[**] Term: 14 Years

[21] Appl. No.: 584,844

[22] Filed: Sep. 19, 1990

[30] Foreign Application Priority Data

Jun. 27, 1990 [JP] Japan 2-21519

[52] U.S. Cl. D24/231

[58] Field of Search D24/169, 232

[57] CLAIM

The ornamental design for a clinical chemistry analyzer, as shown.

DESCRIPTION

FIG. 1 is a perspective view of a clinical chemistry analyzer showing our new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof;

FIG. 7 is a bottom plan view thereof; and,

FIG. 8 is a perspective view thereof, with all covers in open condition.

FIG. 1

FIG. 2

FIG. 3

FIG. 4

FIG. 5

FIG. 6

FIG. 7

FIG. 8
